UNITED STATES PATENT OFFICE.

ANTON S. SIMSACK, OF PHILADELPHIA, PENNSYLVANIA, ASSIGNOR OF ONE-THIRD TO
MORRIS APT, OF PHILADELPHIA, PENNSYLVANIA.

SPARK-PLUG TRANSFORMER.

Application filed February 21, 1927. Serial No. 169,912.

The present invention is directed to a new automotive accessory in the form of an electrical contrivance, adapted for association with the ordinary internal combustion engine 5 spark plug, and as the title implies, the device relates more particularly to a current transformer for disposition between the wire terminal and the binding post of the spark plug.

10 The improvement is characterized by the exceptional simplicity of construction and convenience of arrangement of parts, and is advantageous in that it is in the form of an attachment which may be connected with the ordinary spark plug now marketed and the bared core of the wire terminal, in order to transform the electrical current before it passes through the spark plug.

I aim particularly to provide a structure 20 of this kind which is such as to transform the direct current now used to a high frequency current, such as will produce a high frequency electric spark for release on the interior of the cylinder.

25 Particularly, do I wish to point out that the transformation of the current which takes place when acted upon by the special contrivance is desirable because of the fact that it produces a different character of spark between the main and secondary electrodes, the spark being in the form of a brilliant intense flash as distinguished from a short transient spark such as ordinarily takes place.

30 This achievement, it is believed, will prevent the plugs from becoming fouled, or short circuited by oil and carbon deposits, particularly because the hot spark will burn and loosen the deposits.

35 The construction as well as the arrangement and association of parts will become more readily apparent from the following description and drawings.

In the accompanying drawings:

40 Fig. 1 is a central longitudinal section through a transformer and wire terminal constructed in accordance with the invention.

Fig. 2 is a side elevation of the same, and

Fig. 3 is a transverse cross section.

45 In carrying out the invention, I employ an elongated casing 1 of appropriate insulation material. This is of tubular cross section and preferably composed of hard rubber. Fitted into one end of the casing is a metal plug 2 (preferably brass), having a stop flange 3 and constructed as at 4 to maintain

the retainer 5 in place. This retainer includes a fork 6 of a construction to fit upon the ordinary binding post of a conventional type of spark plug. This plug 2 is knurled on its exterior or corrugated in any suitable manner to facilitate maintenance when assembled in the casing.

50 A somewhat similar plug 7 is fitted into the opposite end, this plug carrying an outstanding flange 8, the periphery of which is formed into a wrench engaging nut. Here again, the plug is of brass and is knurled on its exterior to hold it firmly in place. In fact, these plugs are so tightly fitted in the casing that they provide a hermetic seal. Incidentally, it will 55 be noticed that the plug 7 carries central outstanding screw threaded pointed extension 9 which serves in a manner to be described more in detail at a later point.

50 At this time, I would direct attention to the fact that with this arrangement, a vacuum chamber is formed within the casing, and the electrical transforming means is located in this vacuum chamber. The transforming means comprises a central axially alined rod 80 10 of appropriate insulation material which has its opposite pointed ends fitted into correspondingly shaped sockets, on the inner ends of the plugs 2 and 7.

55 Mounted on this rod, are metal disks 11 of appropriate thickness and diameter. Interposed between each pair of disks is an insulating washer 12 which operates as a spacer, the washer being of a diameter less than the disks. The disks in turn are of a diameter 90 less than the internal diameter of the chamber, in order to provide sparking space 13, around the peripheral portions of the disk. It will be noticed that a coiled spring 14 surrounds one end portion of the rod, bears 95 against an adjacent disk and against the plug 7. This spring provides proper tension upon the disks and washers and holds them securely in place, yet not too tightly.

60 The spring has the additional function of an electric coil. The reference character 15 designates an ordinary electrical conductor having a bared core 16 at one end. The casing of this conductor fits into a socket formed in the coupling 17. The inner end of this 105 socket is conical as at 18 and merges into a central opening and a screw threaded portion formed in the neck 19. The aforesaid pointed extension 9 threads into this neck and binds the strands of the core tightly against 110

the wall of the opening in order to hold the conductor in place.

In practice, it is obvious that the fork 6 on the right hand end of the transformer is connected to the binding post of an ordinary spark plug in the customary manner and that the conductor 15 is coupled with the transformer in the manner shown and described. Then, the current passing from the conductor into the plug is transformed through the action of the multiplicity of disks. The current is intensified and amplified and literally changed from a direct current into a high frequency current. The latter produces the desirable type of spark which, as before indicated, resembles a rather close prolonged flash, instead of the short jumping spark ordinarily provided.

It follows that with this arrangement there will be no pre-ignition nor after-ignition for the flash will last sufficiently long to cause the cylinder to fire at the proper instant.

It is believed that when the description is considered carefully in connection with the drawing, a clear understanding of the construction and operation and advantages of the invention will be had. In view of this, a more lengthy description is thought unnecessary.

While I have described and shown the preferred embodiment of the invention, it is to be understood that minor changes coming with-

in the field of invention claimed may be resorted to if desired.

Having thus described my invention, what I claim as new is:—

As a new product of manufacture, a transformer attachment for ordinary spark plugs, comprising an elongated tubular casing of insulation material, plugs fitted into the opposite open ends of the casing, said plugs being of electricity conducting material, and an axially alined rod of insulation material located centrally on the interior of the casing and having its opposite ends connected with said plugs, a set of metallic rings assembled upon said rods, a ring on one end of said set being in electrical connection with the adjacent one of said plugs, a coiled spring surrounding the rod at the opposite end and engaging the adjacent rings and adjacent plugs, and insulation washers surrounding the rod and interposed between the rings for spacing the rings apart, to provide spark gaps between the peripheral edges of the ring, said washers being of a diameter less than the ring, and said rings being of a diameter, less than the cross sectional diameter of the interior of said casing to provide an annular sparking space around the peripheral portions of the rings, and washers.

In testimony whereof I affix my signature.

ANTON S. SIMSACK.
